UNITED STATES PATENT OFFICE.

THOMAS H. ROYCE, OF BROOKLYN, ASSIGNOR TO BENJAMIN ALTMAN, OF NEW YORK, N. Y.

DESIGN FOR A SKIRT-PATTERN.

SPECIFICATION forming part of Design No. 25,190, dated February 18, 1896.

Application filed January 11, 1896. Serial No. 575,181. Term of patent 14 years.

To all whom it may concern:

Be it known that I, THOMAS H. ROYCE, a citizen of the United States, residing in Brooklyn, Kings county, State of New York, have 5 invented and produced a new and original Design for a Skirt-Pattern, of which the following is a specification.

The essential feature of my design is a skirt-pattern of substantially the outline illustrated in the accompanying drawing, which 10 shows my design.

In the drawing, A is a skirt-pattern which

is bounded by a curved edge *a* contiguous to two radial edges *b* and *c*, which are joined by the curved and gored edges *e f*, whose continuity is broken by a gore *g*. 15

What I claim is—

The design for a skirt-pattern, substantially as herein shown and described.

THOMAS H. ROYCE.
